ABSTRACT OF THE DISCLOSURE

Providing finned tubing having fins integral therewith, severing at least one fin substantially inward towards the tube portion, and then deflecting the fins sufficiently inward towards said tube portion to provide an overlay in contacting arrangement and contiguous with the external surface of the tube portion.

Finned tubing has found extensive and long use in a wide variety of applications wherever a high rate of heat transfer is required. The fins, being bonded to the tubing, provide a large increase in effective surface area and thus correspondingly increase the rate of heat transfer between the medium passing through the finned tubing and the medium on the outside of the tubing.

For example, finned tubing is used extensively in heat exchanger applications wherein condensing, e.g. steam to water, is required. The medium passing through the tubing, being employed at a substantially lower temperature than that being condensed, maintains a largely increased condensing surface at a temperature lower than the temperature of the outside medium and thus provides for increased condensation. Conversely, the cooling medium, rather than passing through the finned tubing, may be employed on the outside with the medium being condensed passing through the inside.

Naturally, finned tubing is not limited to applications wherein a condensing action is required, but rather the application of finned tubing includes heat transfer, or the exchange of heat, when the medium on both sides of the tubing are liquid, or both gaseous, or a combination thereof. Condensation per se may or may not be required depending upon the particular application contemplated.

Finned tubing when employed in a particular heat exchanger may be fitted to material, such as heavier walled conventional tubing, i.e. without fins. Method of joining include, e.g. welding, brazing, mechanical connecting, and employing an adhesive in combination with mechanical connecting. Connections in combination with the use of adhesives are not especially critical and include all phases of lap type joining adaptable to tubing.

Mechanical joining of finned tubing to conventional tubing having a greater wall thickness, however, provides a joint of substantially less mechanical strength than if the finned tubing were of more nearly the same wall thickness since the finned tubing necessarily contributes a lesser amount of metal to the joint than the conventional tubing.

Likewise the difference in wall thickness will, upon cooling after welding, cause an uneven stress pattern to occur at the area of the joint since the cooling rates are necessarily dissimilar and thus also cause a reduction in mechanical strength of the joint.

Thus, it is a particular object of the present invention to provide a method of preparing finned tubing for joining to conventional tubing of a greater wall thickness, and the article produced thereby.

It is an additional object of the present invention to provide a method for increasing the mechanical strength of the joint between the finned and conventional tubing

2

by increasing the wall thickness and to provide an area of the finned tubing more readily adaptable to various methods of joining.

It is a further object of the present invention to provide a process and article aforesaid while retaining the highly desirably characteristics of finned tubing.

It is a still further object of the present invention to provide a simple and expeditious process which accomplishes the aforesaid objects conveniently and at a commercially competitive cost.

Further objects and advantages of the present invention are apparent hereinafter.

FIGURE 1 is a partial perspective view of one end of a finned tubing;

FIGURE 2 is a partial perspective view of one end of a finned tubing showing fins severed at a right angle to the tube portion;

FIGURE 3 is a partial perspective view of one end of a finned tube showing that portion of the fin severed from the remainder of said fin folded longitudinally and downwardly towards the tube portion;

FIGURE 4 is a partial perspective view of one end of a finned tubing showing the folding of FIGURE 3 completed;

FIGURES 5-8 are partial perspective views of alternative embodiments of severing the fin substantially inward towards the tube portion;

FIGURE 9 is a partial perspective view of one end of a finned tubing showing folding of unsevered fins longitudinally and downwardly towards the tube portion.

Briefly, the process of the present invention comprises, providing a finned tubing having fins integral therewith, severing at least one fin substantially inward towards the tube portion, and then deflecting the fins sufficiently inward towards said tube portion to provide an overlay in contacting arrangement and contiguous with the external surface of the tube portion.

Preferably, the attached fins should be of sufficient outwardly extending length so that the external surface of the tube portion will be substantially covered after deflecting to form the overlay. Naturally, the total outwardly extending length of the attached fins may exceed the circumference of the tube portion so that successive overlays may be built up.

Normally, fin tubing comprises a plurality of integral fins, although only one attached fin would be necessary if the outwardly extending length thereof at least substantially equalled the circumference of the tube portion.

Referring to the drawings, FIGURE 1 shows an end portion of a conventional finned tubing, with fins 1 and 2 being affixed to tube portion 3.

FIGURE 2 shows fins 1 and 2 severed inward substantially to tube portion 3 forming separate portions 4 and 5 of each fin substantially freed from the remainder of the fins.

FIGURE 3 shows initial deflection of the freed fin portions and FIGURE 4 shows deflection completed thereby forming a terminal overlay of said deflected fin portions in contacting arrangement and substantially contiguous to the external surface of the tube portion 3. Thus, as shown in FIGURE 4 the arrangement of overlay 6 is readily adaptable to various methods of joining with conventional tubing having a greater wall thickness than that of the finned tubing. In effect, the wall of the finned tube has been doubled in thickness thereby providing additional metal for increased mechanical strength of a subsequent joint to conventional tubing.

If desired, severed fin portions 4 and 5 may be metallurgically bonded to tube portion 3. For example, a bonding agent comprising a lower melting material than that of the severed fin or tube portions may be suitably placed between the inside surface of the severed fin portions 4

and 5, comprising overlay 6 and the external surface of tube 3 and the entire assembly heated sufficiently to cause a metallurgical bond. Any convenient method of introducing the bonding agent may be employed, such as coating the external surface of tube portion 3 before deflecting severed fin portions 4 and 5, or coating those surfaces of severed fin portions 4 and 5 to be substantially contiguous with tube portion 3. After deflection of fin portions 4 and 5, the bonding agent is then in contacting arrangement with overlay 6 and tube portion 5, and the assembly is then ready for heating. Preferably external pressure is applied to the assembly during the heating step to insure continued intimate contact of overlay 6, the bonding agent, and tube portion 3 thereby insuring proper metallurgical bonding.

Metallurgical bonding may be accomplished in other ways, as for example, by pre-heating a die in which severed fin portions 3 and 4 are deflected and contacted with tube portion 3. The combination of heat given up to the assembly and pressure in forming the overlay will provide proper metallurgical bonding.

The method of severing fins 1 and 2 to form severed portions 4 and 5 is not critical and any convenient method such as cutting, blanking, stamping, sawing, etching, etc. may be employed.

Likewise, the method of deflecting severed fin portions 4 and 5 is not critical and methods such as hand working, sawing, rolling, drawing, wiping, forging, vacuum forming, etc. are readily adaptable to the present invention.

If desired, fins 1 and 2 may be deflected to form overlay 6 around at least one end of tube portion 3 without the aforementioned severing operation to form severed fin portions 3 and 4 and the same basic methods of deflection, as aforementioned, are equally adaptable. By this embodiment additional metal is also provided for increased joint strength, regardless of the method of forming the joint. If desired, overlay 6 may also be metallurgically bonded to tube portion 3 as aforementioned.

Finned tubing prepared in accordance with the present invention is readily adaptable to joining to conventional tubing without fins, using conventional methods of joining, as well as to additional finned tubing also prepared in accordance with this invention.

If so desired, both ends of finned tubing may be prepared in accordance with the present invention.

For example, the present invention is readily adaptable to various types of connections employing adhesives. Various connections include insert type connections as well as all types of lap type joining adaptable to tubing such as for example, simple, lap, joggle lap, tapered lap, etc. Suitable adhesives include epoxies, pipe joint cement, rubber based cement, etc.

Mechanical compression fittings may also be employed without encountering the problems attendant with tubing of lesser wall thickness i.e. the increase in effective wall thickness provides the increased mechanical strength requisite for this type of fitting.

Depending upon the relative inside diameter, or bore, of the tubing to be joined, one may be inserted into the other for a suitable distance and then joined in this position. Suitable adhesives, as aforementioned, are also especially useful in this method of joining.

The present invention is also readily adaptable to welding for forming a high strength bond. Heliarc welding, in particular, may preferably be employed due to the increased amount of available metal of overlay 6.

Thus, it may be seen that the present invention provides a simple and expeditious method for preparing finned tubing for joining to conventional tubing of thicker wall diameter whereby increased mechanical strength of

the joint is obtained while maintaining the highly desirable characteristics of finned tubing.

The fin portions may be severed as aforementioned before forming the overlay, or may be formed into the overlay without severing and, if desired, a bonding agent comprising a lower melting material may be employed in order to metallurgically bond the overlay formed with the tube portion.

This invention may be embodied in other forms or carried out in other ways without departing from the spirit or essential characteristics thereof. The present embodiments are therefore to be considered as in all respects illustrative and not restrictive, the scope of the invention being indicated by the appended claims, and all changes which come within the meaning and range of equivalency which are intended to be embraced therein.

What is claimed is:

1. A method of adapting finned tubing for joining to material of greater wall thickness comprising:

(A) providing a heat exchange element comprising a tube, and at least one outwardly extending fin integral therewith, with the total outwardly extending fin length being at least substantially equal to the circumference of said tube; and

(B) deflecting at least one portion of said fin sufficiently inward towards said tube to provide an overlay of said fin in contacting arrangement and substantially contiguous with the external surface of said tube.

2. The method of claim 1, wherein said fin at one end of said tube is deflected sufficiently inward towards one end of said tube to provide an overlay of said fin in contacting arrangement and contiguous with said external surface of said one end of said tube.

3. The method of claim 1, wherein there are two said fins of substantially equal outwardly extending length.

4. The method of claim 1, further providing the step of substantially severing at least one said fin inwardly towards said tube to provide a terminal end portion of said fin before deflecting said fin to form said overlay.

5. The method of claim 3, further providing the step of substantially severing at least one of said fins inwardly towards said tube to provide a terminal end portion of said fin before deflecting said fins to form said overlay.

6. The method of claim 5, wherein said fins have a total outwardly extending fin length substantially equal to the circumference of said tube.

7. The method of claim 3, wherein said fins have a total outwardly extending fin length substantially equal to the circumference of said tube.

8. The method of claim 1, further including the step of metallurgically bonding said overlay to said tube.

9. The method of claim 7, further including the step of metallurgically bonding said overlay to said tube.
